CHILD'S GARMENT

Dorothy J. Buffington, Highland Park, Mich.

Application December 24, 1935, Serial No. 56,055

4 Claims. (Cl. 2—80)

This invention relates to children's sun suits and the object of the invention is to provide a sun suit made from a pair of rectangular pieces of cloth, such as a pair of bandanna handkerchiefs or other material of approximately the same size.

One of the particular objects of the invention is to provide a sun suit which may be made from a pair of rectangular pieces of cloth so that there is no waste whatever in making the same.

10 A further object of the invention is to provide a sun suit which will automatically adjust itself to the child's body and will fit children of different sizes.

Another object of the invention is to provide 15 a sun suit of the character described having a double seat and flared side edges at the bottom and provided with a pocket formed from the material in cutting one of the rectangular cloth sheets.

20 A further object of the invention is to provide a child's sun suit which may be very cheaply manufactured and sold and is attractive in appearance.

These objects and the several novel features of 25 the invention are hereinafter more fully described and claimed and the preferred form of construction by which these objects are attained is shown in the accompanying drawing in which—

Fig. 1 is a perspective view of the sun suit upon 30 a child showing the front of the sun suit.

Fig. 2 is a similar view showing the back of the sun suit.

Fig. 3 is a view of the completed garment from the rear.

35 Fig. 4 is a section taken on line 4—4 of Fig. 3.

Fig. 5 is a section taken on line 5—5 of Fig. 3.

Fig. 6 is a section taken on line 6—6 of Fig. 3.

Fig. 7 is a section taken on line 7—7 of Fig. 3.

The garment is formed from two rectangular 40 pieces of cloth 1 and 2 shown in Figs. 1, 2 and 3.

These two rectangular pieces of cloth are sewed together on the line 3 shown at the bottom of Figs. 3 and 7 and each upturned corner 4 is sewed to its respective fabric piece by the stitching 5 to provide a double seat forward and to the rear of the seam 3, as shown in Fig. 7.

The edges 6 and 7 are not sewn together in order to provide an opening for the child's legs but the edges 8 and 9 are sewn together by the stitching 10 as

50 shown in Fig. 3. The upper corner of the sheet 1 directly above the corner 4 is cut off and the edge is inturned and sewn by the stitching 11 to provide a hem for the elastic band 12 which is secured in the hem by the tacking 13 at each end.

55 In order to obtain the desired fullness in the

front piece 2 of the material, the two pieces of material 1 and 2 are stitched together by the stitching 14 shown in Figs. 3 and 6 and the fabric piece 1 is further gathered by forming inverted pleats 15 by the stitching 16 which is also shown in Fig. 5. By this arrangement the back piece of material 1 is gathered as shown in Fig. 2 and the front piece of material is drawn across the child's chest and up under the arms as shown in Fig. 1.

10 The upwardly extending corner of the fabric piece 2 is provided with a hem 17 through which a cord 18 is inserted and the corner 19 may be turned upwardly as shown in Figs. 1, 3 and 4 if desired and may also be turned downwardly. The cord 18 may be then tied about the child's neck as shown in Fig. 2.

15 In putting the garment on, the child steps through the opening provided at the top between the two pieces of fabric 1 and 2 and by stretching the elastic 12 may draw the garment up over the body so that the legs extend through the open edges 6 and 7 of the garment as will be readily understood from Figs. 1, 2 and 3. The side portions between the stitching 10 and 14 form 20 flared edges 20 as shown in Figs. 1 and 2 and the material cut off from the upper corner of the rectangular fabric piece 1 in forming the hem 11 provides a triangular piece 21 which is sewn 25 on the front of the garment to provide a pocket as shown in Fig. 1.

30 From the foregoing description it becomes evident that the entire rectangular area of both pieces of cloth is used in manufacturing the garment so that there is no waste material and due 35 to the elastic 12 in the hem 11, the garment will automatically adjust itself to the child's body and, at the same time, due to the length of the cord 18, the same sized garment may be worn by different sized children and children of different 40 ages.

Having thus fully described my invention, its utility and mode of use, what I claim and desire to secure by Letters Patent of the United States is—

45 1. A garment comprising two superimposed rectangular pieces of cloth each provided with an inturned corner sewn to the respective piece and the folded edges being sewn together, the diagonally opposite corner of one piece being provided 50 with a tubular portion, a cord extending through said tubular portion, the companion corner of the other piece being cut off and inturned to provide a hem, an elastic extending through the said hem and fastened at opposite ends in the hem, the 55

elastic tending to shorten the hem and a pair of inverted pleats formed in the hemmed piece below the hem, the edges of the two superimposed pieces extending from the hem being sewn together and the edges of the two pieces being also sewn together a second time by a spaced row of stitching extending at a slight angle to the adjacent sewn edges of the two pieces.

2. A garment comprising two superimposed 10 rectangular pieces of cloth each provided with an inturned corner sewn to the other where folded, the inturned corner of each piece being sewn to the body of the piece to provide a double seat, a cord secured to the diagonally opposite corner of 15 one piece and the diagonally opposite corner of the other piece being cut off and inturned to provide a hem, the edges of the two pieces extending from the hem being sewn together, an elastic cord secured in the said hem and a pair of inverted pleats extending downwardly from the hem.

3. A garment comprising two superimposed rectangular pieces of cloth sewn together at one corner, a cord secured to the diagonally opposite 25 corner of one piece and the diagonally opposite corner of the other piece being cut off and turned in to provide a hem, the edges of the two pieces extending from the hem being sewn together, an

elastic secured in the hem and a row of stitching extending from each end of the hem toward the unsewn edges of the rectangular cloth pieces.

4. A garment comprising two superimposed 5 rectangular pieces of cloth, the median line of the garment extending from one corner to a diametrically opposite corner, a short length of the corners at the bottom of the garment lying within the garment, there being stitching to sustain the same in place and determining the width of the 10 garment at the crotch, the two pieces being unstitched on the sides extending in opposite directions from the crotch to provide leg openings and the remaining opposite edges of the two garments being stitched together, the corner of the 15 piece forming the front of the garment opposite the crotch having a hem formed at a point below the terminal point, a neck cord in said hem, the corresponding corner of the back piece being cut therefrom and the cut edge inturned to form 20 a hem, the said corner piece cut from the back piece being stitched to the outer face of the first piece to form a pocket, and an elastic cord in the hem of the back piece tending to draw the uncut portion of the front piece beneath the arms of the 25 wearer.

DOROTHY J. BUFFINGTON.
